UNITED STATES PATENT OFFICE.

GUY A. HAMILTON, OF LEAVENWORTH, WASHINGTON.

POST-OFFICE BOX.

1,249,952.

Specification of Letters Patent. Patented Dec. 11, 1917.

Application filed February 7, 1916. Serial No. 76,834.

To all whom it may concern:

Be it known that I, GUY A. HAMILTON, a citizen of the United States, residing at Leavenworth, in the county of Chelan and 5 State of Washington, have invented new and useful Improvements in Post-Office Boxes, of which the following is a specification.

This invention relates to improvements in postoffice boxes and especially with reference to notice displaying and locking devices for arrangement on an attachment to the inner side of the door of a post office box to indicate to user of the box when the box rent is due and to also lock the door against 10 being opened from the outside by the use of a key and to indicate an announcement to the user of the box that the box is closed, the object of my invention being to provide improved devices of this kind which are 15 cheap and simple and which may be readily attached to the inner side of a post-office box door of usual form.

The invention consists in the features of construction, combination, and arrangement of devices, hereinafter described and 20 claimed.

In the accompanying drawings:—

Figure 1 is an elevation of the inner side of a post-office box door provided with an 25 announcing and door locking devices constructed and arranged in accordance with my invention showing one of the announcing devices in normal position out of the way and the other arranged in displaying 30 and door locking position.

Fig. 2 is a detail sectional view on the plane indicated by the line *a—a* of Fig. 1 through the door and also through the frame which forms the front side of the 40 boxes, and showing one of the announcing devices in locking position.

For the purposes of this specification, the front or metal frame of a mail box or series of mail boxes is indicated at 1, the sides of 45 a mail box being indicated at 2, and the door being indicated at 3. The frame, the door, and the box are of the usual construction and such as are commonly employed in post-offices and the door is shown as provided with the usual key operated lock 4, and is also provided at one side with hinges 5 and with a square opening which is covered by a glass pane 6. In accordance with 50 my invention, I provide a pair of announcing devices or levers 7, 8, which are arranged at opposite sides of the door on the

inner side thereof and are pivotally connected to the door as by means of screws 9, 10, respectively. The screw 9 is near the upper end of the announcing device 7 so 60 that when the latter is turned across the glass opening 6 to display a notice thereon, the pivotal end of said announcing device will not project beyond the hinged side of the door and hence the door may be opened 65 from the outside by an authorized person having a key to the lock. Said announcing device 7 is provided with a suitable inscription such as "Box rent due," which when said announcing device is extended across 70 the glass opening, will be displayed to the user of the box.

The pivot 10 of the announcing device 8 is spaced from the upper end of said device, and said device is of such length that its 75 upper arm 11, when said device is turned on its pivot and arranged across the glass opening 6, will extend beyond the edge of the door opposite the hinges 5 and engage 80 on the inner side of the frame, or common front of the box, and thereby lock the door on the inner side so that it cannot be opened from without by a person having a key to the lock. The pivot 10 of the said announcing device serves to hold the extension of 85 the announcing device frictionally against the frame when the announcing device is in displayed position and said pivot also enables said announcing device to lie by its own gravity normally in withdrawn position. This announcing device 8 has a suitable inscription such as "Box closed," which when displayed, indicates to the user of the box that he can no longer use it until after 90 he has paid the rent or made whatever arrangement may be required with the postmaster. The announcing device 8 may be used at any time by the postmaster, when for any reason he desires the holder of the box to call at the window. 95

My improved announcing devices are especially valuable and practical for use in collecting box rents due at the end of each quarter. They enable the use of box rent tags to be dispensed with and effect a great 100 economy in the management of the box by the postmaster and the collecting of the rents.

While I have herein shown and described a preferred form of my invention, I would 110 have it understood that changes may be made in the form, proportion, and construc-

tion of the several parts without departing from the spirit of the invention and within the scope of the appended claim.

Having described the invention, what is claimed is:

5 In a post office box, a frame having a door opening, a mail box door arranged to close in said opening and hinged to the frame at one side of said opening, the free edge of 10 the door and the corresponding portion of the frame being arranged to form a lap joint between the door and the frame when the door is closed and said door and frame having plane flush inner surfaces, the said 15 door being provided with an opening, and an announcing device comprising a bar pivotally mounted on the inner side of the door near the free edge and upper side of the latter, bearing directly against the door 20 and provided with an extension at its upper

end adapted when said announcing device is in displayed position to project beyond the free edge of the door and engage the corresponding side of the frame and thereby lock the door, the pivot of the announcing device comprising a screw, the arrangement of the announcing device in direct contact with the door and the frame serving to hold the extension of the announcing device frictionally against the frame when the announcing device is in displaying position and the pivot also enabling the announcing device to lie by its own gravity normally in withdrawn position.

In testimony whereof I affix my signature 35 in presence of two witnesses.

GUY A. HAMILTON.
